UNITED STATES PATENT OFFICE.

ESEK BUSSEY, OF TROY, NEW YORK, ASSIGNOR TO HIMSELF AND
CHARLES A. MCLEOD, OF SAME PLACE.

IMPROVEMENT IN BASE-BURNING STOVES.

Specification forming part of Letters Patent No. 152,597, dated June 30, 1874; application filed
January 3, 1874.

To all whom it may concern:

Be it known that I, ESEK BUSSEY, of Troy, in the county of Rensselaer and State of New York, have invented Improvements in Base-Burning Stoves. The following description, taken in connection with the accompanying plate of drawings hereinafter referred to, forms a full and exact specification, wherein are set forth the nature and principles of the invention, by which the same may be distinguished from others of a similar class, together with such parts thereof as are claimed as new and are desired to be secured by Letters Patent of the United States.

My invention relates to that class of heating apparatus commonly known as base-burning stoves; and the nature thereof consists in certain improvements in the details of the construction of the same, whereby the grated fire-pot is inclosed by a dead-air chamber for the purpose of preventing the circulation of air, and thereby producing a better illumination. It also consists in the employment of an upper and a lower fire-pot so arranged with reference to each other as to form an annular opening or space somewhere between the top of the upper fire-pot and the top of the lower fire-pot, and opposite or nearly opposite mica lights in the casing.

In the accompanying plate of drawings, which illustrate my invention, and in which corresponding parts are designated by similar letters, Figure 1 is an elevation of the exterior of a stove having my improvements applied thereto. Fig. 2 is a vertical section taken in the line indicated by the letters *x x* of Fig. 1. Fig. 3 illustrates in plan that part of the stove which forms the base of the dead-air chamber.

In the drawing referred to the upper part of the body or casing of the stove, designated A, is of the ordinary construction, and is provided with the usual mica windows B, affording an unobstructed view of the surface of the fire above the fire-pots and at the base of the magazine. At the point *a* the annular top of the upper fire-pot E meets the casing and forms so close a connection therewith as to prevent the air from passing upward, except

through the grated portion thereof. Just below the grated fire-pot E the lower fire-pot D is connected by the annular partition H to the casing of the stove, in such a manner as to form about the said grated fire-pot, and between the same and the mica lights I in the casing, a dead-air chamber, K. By this construction the air which enters the ash-pit can only pass upward through the bottom of the lower fire-pot, and is not allowed to come in contact with the outer surface of the upper grated fire-pot. The bottom of the said fire-pot projects outward sufficiently to prevent the unburnt coals from falling out, and is provided with a series of apertures, L, of sufficient size to admit of the removal of slate and clinkers from above the grate and on all sides of the same. The lower part of the said casing of the stove is provided with a series of doors, M, through which a poker may be introduced for the purpose of removing the clinkers, as aforesaid.

The grate O may be rotated upon a central pivot, having its bearings in the cross-piece p, attached to the annular bottom of the fire-pot.

Having described the construction and operation of my invention, I will indicate in the following clauses what I claim and desire to secure by Letters Patent of the United States—that is to say:

1. The combination of the following elements: The upper fire-pot, the lower fire-pot, and windows in the casing opposite or nearly opposite the space between the fire-pots.

2. The combination of the following elements: The upper fire-pot, the lower fire-pot, the opening between the fire-pots, the dead-air chamber, and the windows in the casing opposite the dead-air chamber, as described.

3. The combination of the upper fire-pot, the lower fire-pot, and the dead-air chamber, as and for the purposes described.

In testimony that I claim the foregoing I have hereunto set my hand this 22d day of December, 1873.

ESEK BUSSEY.
